UNITED STATES PATENT OFFICE.

ARTHUR O. BROOKE, OF KANSAS CITY, MISSOURI.

INTERNAL-COMBUSTION ENGINE.

1,134,667.

Specification of Letters Patent.

Patented Apr. 6, 1915.

Application filed April 19, 1913. Serial No. 762,206.

To all whom it may concern:

Be it known that I, ARTHUR O. BROOKE, a citizen of the United States, residing at Kansas City, in the county of Jackson and 5 State of Missouri, have invented certain new and useful Improvements in Internal-Combustion Engines, of which the following is a specification.

This invention relates to internal combustion engines, and particularly to appliances designed to utilize kerosene or other hydrocarbons of varying grades or qualities as a fuel which will answer satisfactorily for the 10 operation of engines of this type.

One object of the invention is to improve 15 the construction set forth in my pending application, Serial No. 753,973, for improvements in internal combustion engines, filed March 8, 1913, in which means is provided 20 for vaporizing the fuel and generating steam by the heat of the exhaust, mixing the steam with air, and thereafter intermingling these 25 gases in the intake manifold. In the present instance, I also vaporize the fuel directly 30 from the heat of the exhaust gases by passing the fuel supply for practically its entire course through the exhaust manifold, whereby it is completely vaporized by the time it 35 has reached the point for introducing the air to be mixed therewith. In this way the construction is rendered simpler by dispensing 40 with a number of the parts of my other apparatus and at the same time more fuel is exposed to the action of the heat.

Another object is the production of a 45 device in which there will be a thorough mixture of the fuel vapor with the air, and in which the control of the action of the fuel supply will be rendered largely automatic in accordance with the rate of the fuel consumption.

With these and other objects in view, as will hereinafter appear, the invention consists in certain novel and peculiar features 45 of construction as hereinafter described and claimed, and to afford a complete understanding of the same, reference is to be had to the accompanying drawings, in which—

Figure 1 is a side elevation of the general 50 plan of my apparatus as applied to the engine of an automobile, the view being partly broken away to show the arrangement of the oil feed; Fig. 2 is a vertical section along the line II-II of Fig. 1, illustrating the 55 passages for the fuel vapor and air from

the exhaust tube to the intake manifold; and Fig. 3 is a section along the line III-III of Fig. 2.

In the drawings, an internal combustion engine 2 is shown in the usual position occupied by it upon the chassis 4 of an automobile, and provided with the usual intake manifold 6 and exhaust manifold 8. Communicating with the intake manifold 6 is an intake port 10 controlled by a throttle valve 12 carried in an overlying casing 14. This casing 14 is provided with an auxiliary air valve 16 held normally closed by a coil spring 18 the tension of which may be adjusted by a nut 20.

Communicating with the casing 14 is an air mixing tube 22 leading from an air-inlet casing 24 which is mounted upon the exhaust manifold 8 and secured thereto by U-bolts 26. This casing has air inlet passages 25 between it and the underlying exhaust manifold in passing through which the air is heated.

The liquid fuel tube 28 extends through the exhaust manifold and has its discharge 30 terminal located just within the receiving end of the tube 22, i. e., just above the point where the latter communicates with the casing 24. One portion of the tube 28 extends 35 at an incline from the engine, as shown in Fig. 1, from where the tube, still following the exhaust, extends horizontally, finally leaving the exhaust and extending up to a valve chamber 30. Within this chamber is 40 a valve 32 operated by a float 34, which, supported upon the liquid in the chamber, tends 45 to throw the valve to close the entrance into the chamber from a supply tube 36 which 50 communicates with the fuel reservoir 38.

From the above it will be understood that 55 the fuel is vaporized upon passing through the exhaust manifold 8, which is kept at a high temperature due to the discharge of the hot gases therethrough. The feed tube 28 extends for practically its whole length 60 through the exhaust, and is consequently subjected to the full heating action of the 65 exhaust gases. Normally the liquid fills the horizontal run of the tube 28 and stands in 70 the inclined portion of the tube at the height of the liquid in the valve chamber 34, so 75 that at all times the fuel is being heated throughout this portion of the tube, and through an additional higher portion of the 80 tube corresponding to the amount the valve 85

12 is thrown open; *i. e.*, as the speed of the engine is increased, the suction through the tube 28 is increased and a correspondingly long column of the liquid is automatically subjected to the heating action of the exhaust. As the liquid is vaporized, it passes out through the discharge opening into the tube 22 where it is mixed thoroughly with the heated air entering through the passages 10 25 of the casing 24. From this point the hot mixture is drawn down into the casing 14 and through the port 10, the valve 18 acting automatically, as usual, to let in air when the capacity of the inlet passages 25 has been exceeded.

From the foregoing description it will be apparent that I have provided a very simple and efficient appliance for carrying out the objects above enumerated, and while I have 20 shown and described the preferred embodiment of my invention, I wish it understood that I reserve the right to make any such changes and modifications as may properly fall within the spirit and scope of the appended claims.

I claim:

1. In an internal combustion engine, the combination with the intake manifold and the exhaust manifold, of a liquid fuel supply, and a fuel supply tube having a horizontal run beneath the level of said fuel supply and an upwardly inclined run leading from the horizontal run to the intake manifold, said runs passing through the exhaust manifold and the inclined run having the fuel standing therein normally at a height above the level of the horizontal run, whereby the fuel is vaporized by the heat

from the exhaust and its level varied in accordance with the speed of the engine. 40

2. In an internal combustion engine, the combination with the intake manifold and the exhaust manifold, of a liquid fuel supply, a fuel supply tube having a horizontal run beneath the level of said fuel supply 45 and an upwardly inclined run leading from the horizontal run to the intake manifold, said runs passing through the exhaust manifold and the inclined run having the fuel standing therein normally at a height above 50 the level of the horizontal run, whereby the fuel is vaporized by the heat from the exhaust and its level varied in accordance with the speed of the engine, and means for supplying air to said fuel after the latter is 55 vaporized and before it reaches the intake manifold.

3. In an internal combustion engine the combination with an intake manifold, an exhaust manifold, means for obtaining heated air from around said exhaust manifold, a fuel supply tube within said exhaust manifold, and opening out of said manifold in a vertical direction and within said air heating means, an inverted U-shaped tube 65 extending from said air heating means to said intake manifold, a throttle valve located near said intake manifold and an auxiliary air intake located at the end of said tube and near said intake manifold. 70

In testimony whereof, I affix my signature, in the presence of two witnesses.

ARTHUR O. BROOKE.
